(57) **CLAIM**

The ornamental design for a reservoir for a hummingbird feeder, substantially as shown and described.

DESCRIPTION

FIG. 1 is a top front perspective view of a reservoir for a hummingbird feeder showing my new design;

FIG. 2 is a bottom rear perspective view thereof;

FIG. 3 is a top plan view thereof;

FIG. 4 is a bottom plan view thereof;

FIG. 5 is a left elevational view thereof;

FIG. 6 is a right elevational view thereof;

FIG. 7 is an exploded top front perspective view of a hummingbird feeder and the reservoir shown in FIGS. 1-6 forming a part thereof;

FIG. 8 is an exploded bottom rear perspective view of the hummingbird feeder and reservoir shown in FIG. 7;

FIG. 9 is an exploded top plan view of the hummingbird feeder and reservoir shown in FIG. 7;

FIG. 10 is an exploded bottom plan view of the hummingbird feeder and reservoir shown in FIG. 7;

FIG. 11 is an exploded left elevational view of the hummingbird feeder and reservoir shown in FIG. 7;

FIG. 12 is an exploded right elevational view of the hummingbird feeder and reservoir shown in FIG. 7;

FIG. 13 is a top front perspective view of the hummingbird feeder and the reservoir forming a part thereof shown in FIG. 7;

FIG. 14 is a bottom rear perspective view of the hummingbird feeder and reservoir shown in FIG. 7;

FIG. 15 is a top plan view of the hummingbird feeder and reservoir shown in FIG. 7;

FIG. 16 is a bottom plan view of the hummingbird feeder and reservoir shown in FIG. 7;

FIG. 17 is a left elevational view of the hummingbird feeder and reservoir shown in FIG. 7; and,

FIG. 18 is a right elevational view of the hummingbird feeder and reservoir shown in FIG. 7.

The broken lines are for illustrative purposes only and form no part of the claimed design.
